UNITED STATES PATENT OFFICE.

EDITH G. HEFFNER, OF DUBOIS, PENNSYLVANIA.

ATTACHMENT FOR WASHBOARDS.

1,404,696.

Specification of Letters Patent. Patented Jan. 24, 1922.

Application filed March 4, 1916. Serial No. 82,175.

To all whom it may concern:

Be it known that I, EDITH G. HEFFNER, a citizen of the United States, residing at Dubois, in the county of Clearfield and State 5 of Pennsylvania, have invented certain new and useful Improvements in Attachments for Washboards; and I do hereby declare the following to be a full, clear, and exact description of the invention, such as will enable others skilled in the art to which it 10 pertains to make and use the same.

The primary object of this invention is to provide a novel type of soap holder designed to be associated with any type of 15 wash board, and effectively hold and house the soap so as not to come in contact with the washing liquid in the tub, when the soap is not in use.

Another object of the invention is to provide a soap holder carrying out the above 20 object, which shall be of simple and durable construction and which has a novel type of closing lid which can be conveniently and expeditiously moved to either open or closed 25 position.

Other objects will appear and be better understood from that embodiment of my invention of which the following is a specification, reference being had to the accompanying drawing forming a part thereof in 30 which,—

Figure 1 is a front elevation of the upper end of the wash board and showing the soap holder applied thereto,

Figure 2 is a section taken on the line 2—2 of Figure 1,

Figure 3 is a detail section taken through the soap holder, and

Figure 4 is a detail plan view showing 40 the operating means for the lid or closure of the receptacle.

Referring to the drawing more in detail, the letter A designates a wash board of ordinary construction having the usual trans- 45 verse upper strip B secured thereto.

The upper end of the operative face of the wash board is provided with a transverse strip 1 which underlies the adjacent edge of the strip B of the frame of the wash 50 board and has its outer face beveled as shown at 2.

Associated with the upper end of the op-

erative face of the wash board is a soap holder designated as an entirety by the numeral 3 and consisting of a receptacle which 55 is of substantially frustopyramidal shape having its forward end resting on the adjacent face of the wash board. The receptacle 3 has one side thereof engaging the beveled face of the strip 2 and is secured 60 thereto by means of the fastening elements 4 which extend through the said face of the receptacle 3 and through the strip 1 and the strip B, as shown more particularly in Figure 2 of the drawing.

As shown in Figure 1 of the drawing the receptacle 3 is located adjacent one side of the wash board and is normally closed by means of a lid 5 which has a marginal lip 6 thereon which extends beyond the adjacent side of the receptacle 3. The lid 5 has hinge connection with the upper side of the receptacle 3 by means of the hinges 7 and the upper edge of the lid is provided on opposite sides of the hinges 7 with sleeves 8 75 which receive one end of an operating rod 9, said operating rod being secured within the sleeves in any suitable manner. The other end of the operating rod 9 extends beyond the adjacent side of the board A and 80 is terminally provided with a manipulating handle 10. When the handle 10 is depressed the rod 9 will be rotated, and by virtue of its connection with the sleeves 8 on the lid 9 will result in the raising of the lid to 85 open position.

By virtue of the configuration of the receptacle 3, the soap, when placed within the same, will be directed by the lower inclined wall of the receptacle toward the lid 5, so 90 that when the lid is raised the soap will be positioned at a point where it can be conveniently grasped by the operator's hand.

Having thus described my invention, what I claim as new is:—

1. In combination with a washboard, a soap receptacle carried by the washboard and mounted in an upper corner of the washboard, a cover for said receptacle hinged at the upper side, a rod having an 100 axis adjacent the hinge extending beyond the margin of the washboard and adapted to be manually engaged beyond said edge for raising said cover.

2. In combination with a washboard, a soap receptacle carried by the washboard, a cover for said soap receptacle hinged at one edge of the receptacle, a tube mounted upon the receptacle cover in juxtaposition to said edge, a rod carried by the tube and extending beyond the margin of the washboard, and a member carried by the rod beyond said margin extending on the opposite side of said hinge from said cover substantially coplanar with the cover.
- 5 In testimony whereof I affix my signature in presence of two witnesses.

EDITH G. HEFFNER.
